UNITED STATES PATENT OFFICE.

JULIUS KAHN, OF DETROIT, MICHIGAN, AND THOMAS HENRY KANE, OF YOUNGSTOWN, OHIO, ASSIGNEES TO TRUSSLED CONCRETE STEEL COMPANY, OF DETROIT, MICHIGAN, A CORPORATION OF MICHIGAN.

REINFORCED EXPANDED METAL.

1,111,838.

Specification of Letters Patent. Patented Sept. 29, 1914.

Application filed July 19, 1911. Serial No. 639,272.

To all whom it may concern:

Be it known that we, JULIUS KAHN, a citizen of the United States, residing at Detroit, in the county of Wayne and State of Michigan, and THOMAS H. KANE, a citizen of the United States, residing at Youngstown, in the county of Mahoning and State of Ohio, have invented a new and useful Reinforced Expanded Metal, of which the following is a specification.

This invention relates to means for stiffening and otherwise strengthening ribbed expanded sheet metal, and the objects of this invention are, to provide means for preventing further expansion of ribbed metal on lines at an angle to the ribs, and to so combine a series of parallel rods with ribbed expanded metal as to better adapt the new structure to resist the various stresses set up by loads in composite slabs wherein this new structure is employed as a reinforcement.

In the accompanying drawings, Figure 1 is an edge view of a sheet of ribbed expanded metal with reinforcing rods secured to the ribs. Fig. 2 is a plan of the same. Fig. 3 is an edge view of a similar sheet of metal with reinforcing rods extending through the sides of the ribs. Fig. 4 is a plan of the same. Fig. 5 is an edge view of a similar sheet of metal with the reinforcing rods secured to the bases of the ribs. Fig. 6 is a plan of the same. Fig. 7 is an end view of a roll of the material shown in Fig. 5.

Similar reference characters refer to like parts throughout the several views.

The expanded metal shown in the drawings is that of the Kahn Patent No. 987,374, dated March 21, 1911, but the present system of reinforcement may be employed in connection with any other type of ribbed expanded metal.

The sheets of expanded metal shown are formed of a series of longitudinal ribs or beams 1, generally U shaped in cross section, and longitudinally extending narrow strands 2. These strands and ribs connect to the ties 3, which in turn, are joined midway between the strands by the small V shaped saddles 4. All the parts are integral with each other. The ribs 1 are preferably so formed that the outer rib of one sheet will fit into the outer rib of the next sheet, so that continuity of structure is attained.

As all the ribs 1 and strands 2 are parallel

to each other, this material is admirably adapted to resist tension stresses parallel to these ribs. But stresses at right angles to these ribs and strands are liable to open up the ribs and crack the plastic material in which the expanded metal is incased.

The drawings show reinforcing rods 6, 7 and 8, extending substantially at right angles to the ribs 1, and secured thereto at the tops, intermediate the tops and bases, and at the bases, respectively, depending upon the choice of the engineer or designer. The rods 6 may be secured to the tops of the ribs of any ribbed metal in any desired manner, preferably by the well known process of "spot-welding", or by soldering. Where the rods 7 are passed through holes punched in the sides of the ribs, the rods may be secured to the sheet metal or not, as desired. The rods pass through the two over-lapping ribs at the edges of adjacent sheets and thus secure the sheets together. As these rods will resist the cross stresses, a union between them and the ribs is not absolutely necessary.

The rods 8 are secured to the lateral flanges at the bases of the ribs, a structure which may be preferable to the others under certain conditions, as when face down in the bottom of a reinforced slab. The spacing of these rods 6, 7 and 8, and their sizes will depend upon the stresses which occur in the slabs in which the metal is embedded. These sheets, which may be constructed the full size of a partition or roof panel at the factory, may be rolled up for shipment as indicated in Fig. 7. When the edges of a sheet of this reinforced expanded metal are secured in position, plaster may be applied to both sides and the partition or the roof slab will be finished. The dimensions of the spans will determine the sizes and numbers of the ribs 1 and the thickness of the sheet metal.

Having now explained our improvements, what we claim as our invention and desire to secure by Letters Patent is:—

100

1. A reinforced expanded metal comprising parallel ribs and strands of entire metal and open-work metal between them, and metal rods rigidly attached at intervals to said ribs and extending at substantially right angles to the same to prevent further expansion of the open-work metal.

2. A new article of manufacture, consist-

- ing of a sheet of reinforced expanded metal, comprising parallel ribs and open-work metal between the ribs, and metal rods rigidly attached at intervals to the walls of said 5 ribs and extending at substantially right angles to the ribs to prevent extension of the sheet at right angles to said ribs.
3. A new article of manufacture consisting of reinforced expanded metal comprising alternate bands of expanded metal and parallel ribs, U-shaped in cross-section, and rods extending at substantially right angles to the ribs and attached to both walls thereof to prevent the ribs from spreading.
- 10 15 4. An expanded metal structure including reticulated web portions and ribs in-

tegral with said portions and alternating therewith, said ribs being U-shaped in cross section and closed at one side only and the opposite walls of each rib having a rigid 20 uniting connection at intervals.

In testimony whereof we have each signed this specification in the presence of two subscribing witnesses.

JULIUS KAHN.
